UNITED STATES PATENT OFFICE.

JOHN JAKOB SCHOENINGER, OF BROOKLYN, NEW YORK.

BRACELET.

1,231,796.

Specification of Letters Patent.

Patented July 3, 1917.

Application filed January 22, 1917. Serial No. 143,558.

To all whom it may concern:

Be it known that I, JOHN J. SCHOENINGER, a citizen of the United States, and a resident of the borough of Brooklyn, county of 5 Kings, city and State of New York, have invented certain new and useful Improvements in Bracelets, of which the following is a specification.

My improvements relate to means for de- 10 tachably securing together the articulated wings or sections of a bracelet. The invention consists in the specific construction and arrangement of parts shown and described— distinctive features being the formation of 15 the bracelet with a major tubular section or wing housing the latch mechanism, and a minor section or wing of filigree work; the form of latch; and the use of a relatively long latch spring, all as hereinafter fully set 20 forth.

In the accompanying drawings,

Figure 1, is a front edge view of my improved bracelet;

Fig. 2, is a side view thereof;

Fig. 3, is a sectional view upon an enlarged scale showing the internal construction of the major wing or section, with the latch open and the minor wing or section released therefrom;

Fig. 4, is a sectional detail showing the latch closed;

Fig. 5, is a similar view showing a modification.

The major wing or section M, of the bracelet is of tubular form and preferably although not necessarily of circular form in cross section, and is approximately three times as long as the minor wing or section N, which is articulately connected to one end 40 of said major section M, by any suitable mechanical expedient, as by the pintle p.

The minor section N, is formed, by preference, of open filigree work of any desired design or configuration, and is the ornate 45 part of the bracelet, while the major section M, affords the requisite strength as well as a housing for the latch C, and its adjunct, the spring S, the main function of which is to tend constantly to thrust said latch outward through the open end m, of the said major section M.

The latch member C, consists essentially of a single piece of elastic resilient metal bent over upon itself to form the coupling 55 arm c, having the hook c', and the locking arm c², provided with the nail stud or

shoulder c³, adapted to protrude through the hole m', formed for it in the major section M, adjacent to the open end m, thereof, as shown in Figs. 2, 4, and 5. The resiliency 60 of the latch C, and particularly of its loop portion c⁴, holds it in this locked position, while admitting of the depression of said nail stud c³, sufficiently to allow the spring S to force the latch member C, outward until 65 said nail stud c³, contacts with a shoulder m², formed for the purpose at the open end m, of the major member M.

The coiled spring S, at its inner end s, rests against a shoulder m³, within the 70 major member M, and this shoulder m³, may consist of the inner extremity of the knuckle piece m⁴, through which the pintle p, passes, or of a separate rest piece or bearing situated elsewhere in the tube M. I prefer to use 75 (though not necessarily) a spring occupying substantially the full length of the tube as shown in Fig. 3, because the action of such a long spring is less abrupt and violent than would be that of a shorter spring, which 80 would have to be stiffer in proportion to its length, or rather lack of length. The long spring also affords less initial resistance to the pushing in of the latch member C, when it is desired to bring the nail stud c³, into 85 coincidence with its socket m'.

The loop c⁴, of the latch member C, may simply rest against the outer end of the spring S, as shown in Fig. 5, in which case the shoulder m², is relied upon to prevent the 90 escape of said latch member C, or the latter may be positively attached to the spring S, by a link s', as indicated in Figs. 3, and 4.

The minor section N, is formed with a free end loop or cross bar n, for engagement 95 with the hook c'; and the latter is of sufficient length to act as a nail contact c⁵ by means of which the latch member C, may be forced back against the resistance of the spring S, until its stud is in coincidence 100 with the hole m'.

This combination of major tubular section M, and minor filigree section N, affords a novel and unique structural effect susceptible of artistic treatment; while the latch member C, and maximum length of spring S, insure ease of connection or release with the avoidance of objectional "snap" or resistance. 105

What I claim as my invention and desire 110 to secure by Letters Patent is,

1. A bracelet comprising a major tubular

- section, a minor section pivotally connected thereto at one end, a spring within the major section, a latch member bearing against and forced outward by said spring at the other 5 end of the major section and comprising a resilient portion with an outwardly extended projection for coöperation with an opening in the major section, the other end of said latch member protruding through the adjacent end of the major section for coöperation with the minor section, the latch end of the major section having an interior shoulder for coöperation with the projection on the latch member.
- 15 2. A bracelet comprising a major tubular section, a minor section pivotally connected thereto at one end, a spring within the major section, a latch member bearing against and

forced outward by said spring at the other end of the major section and comprising a resilient portion with an outwardly extended projection for coöperation with an opening in the major section, the other end of 20 said latch member protruding through the adjacent end of the major section for coöperation with the minor section, the latch end of the major section having an interior shoulder for coöperation with the projection on 25 the latch member, the free end of the minor section having an opening therethrough and the free end of the latch member having an angular terminal for coöperation therewith. 30
